Inventor:

Richard B. Cavanagh,
By his Attorney.

F. W. Barnacle,

UNITED STATES PATENT OFFICE.

RICHARD B. CAVANAGH, OF WASHINGTON, DISTRICT OF COLUMBIA, AS-SIGNOR, BY MESNE ASSIGNMENTS, TO THE KEMPSHALL MANUFACTURING COMPANY, A CORPORATION OF NEW JERSEY.

GOLF-BALL.

SPECIFICATION forming part of Letters Patent No. 710,753, dated October 7, 1902.

Application filed July 30, 1902. Serial No. 117,607. (No model.)

To all whom it may concern:

Be it known that I, RICHARD B. CAVANAGH, a citizen of the United States, residing in Washington, in the District of Columbia, have 5 invented certain new and useful Improvements in Golf-Balls, of which the following is a specification.

This invention relates to golf-balls; and its object is to reduce the cost and improve the 10 durability and other qualities of the balls.

Some of the golf-balls now in use are so lively that they meet with disfavor with many players, since it is impossible to make accurate puts and approaches. My improved ball 15 combines the feature of exceedingly low price and durability and avoids the disadvantage of being too lively for a short game, while well adapted for a long flight when given a heavy blow.

20 In the accompanying drawings, Figure 1 shows, partly in section, one form of golf-ball made in accordance with my improvements. Fig. 2 shows tense windings of tape forming part of the filling of the ball.

25 For a center piece A, I preferably employ a sphere consisting of sawdust, ground cork, or other comminuted material mixed with a compound of glue or glycerin or any other suitable viscous or colloid mixture. This 30 sphere is preferably formed under great pressure, so that the comminuted material is compressed and the whole sphere is highly compacted. The comminuted material is indicated at A' and the cement at A''. The sphere

35 A, I inclose in windings B, of tape or bands, preferably elastic and highly tensioned. For these windings rubber bands may be used, if desired. The layer B holds the sphere A under pressure and aids in the flight of the ball. To 40 the windings I apply a coating or layer of shellac mixture C. This coating or layer may be thin and owing to its adhesiveness and resiliency improves the playing qualities of the ball, besides retaining the windings B firmly in place, and thereby rendering the 45 ball more stable under a blow. Upon the layer C, I apply a cover E, of gutta-percha,

which adheres to the shellac mixture and preferably holds the filling of the ball in a state of compression. The shellac mixture forms 50 a reinforcement for the gutta-percha shell. If desired, the windings may be coated with shellac mixture during the winding operation, so that the shellac may permeate the sphere B, as well as forming a coat thereon. 55

It will be seen that the sphere A is provided with a layer B of longitudinally-tensioned windings, whereby undue disturbance of said sphere under a blow is prevented and undue distortion of the filling and cover of the ball 60 is avoided. The comminuted material and the glue compound are sufficiently springy to enable the ball to make a long flight under a heavy blow, while the ball is comparatively dead under a light blow, thereby meeting the 65 requirements of the game.

Variations may be resorted to within the scope of my improvements.

Having described my invention, I claim—

1. A golf-ball comprising a sphere of compressed comminuted material, a layer of rubber thereon, a layer of shellac mixture, and a cover of gutta-percha. 70

2. A golf-ball comprising a sphere of comminuted material mixed with a compound of 75 glue and glycerin, tense windings of binding material thereon, a layer of shellac mixture upon said windings, and a hard cover.

3. A golf-ball comprising a sphere of comminuted compressed cork, a layer of windings of elastic material thereon, a coating of shellac mixture, and a cover of gutta-percha. 80

4. A golf-ball comprising a yielding sphere, layer of tense windings of elastic material upon said sphere, a layer of shellac mixture 85 upon said windings, and a cover of plastic material.

5. A golf-ball comprising a sphere of compressed comminuted material mixed with glue, a layer of tense elastic windings thereon, a layer of shellac mixture upon said windings, and a gutta-percha cover. 90

6. A golf-ball comprising a sphere of gutta-percha, and a mixture of comminuted mate-

rial and adherent material, and tense windings of binding material permeated with a shellac mixture.

7. A golf-ball comprising a sphere of com-
5 minuted material mixed with a compound of
glue and glycerin, tense windings of binding
material thereon, a layer of shellac mixture

upon said windings, and a hard cover holding
said members under compression.

RICHARD B. CAVANAGH.
